[57] CLAIM

The ornamental design for the touch video graphic icon for image shift on a portion of a display screen, as shown and described.

DESCRIPTION

FIG. 1 is a front view of a touch video graphic icon for image shift on a portion of a display screen showing our new design;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof;

FIG. 6 is a front view of a sixth embodiment thereof;

FIG. 7 is a front view of a seventh embodiment thereof; and,

FIG. 8 is a front view of a eighth embodiment thereof.

The broken line drawing of an undefined portion of a display screen in all views is for illustrative purposes only and forms no part of the claimed design.
